RELAY

Ralph M. Heintz, Cleveland, Ohio, assignor to
 Jack & Heintz, Inc., Bedford, Ohio, a corpora-
 tion of Ohio

Application July 7, 1942, Serial No. 450,039

4 Claims. (Cl. 200—171)

This invention relates to electromagnetic relays and has particular reference to solenoid operated relays for use in the power circuits of electric power consuming devices such as engine starters and the like.

The general object of the invention is to provide an improved small and compact but heavy duty relay for controlling circuits carrying large currents.

A particular object of the invention is to provide an improved relay for installation in engine starters, which will meet the requirements of aircraft use.

A further object is to provide a relay and terminal assembly of the type described which may be built up from a plurality of sub-assemblies to facilitate production of the device in quantity and dismantling for repair or replacement of parts.

These and other objects and advantages will become apparent to those skilled in the art as the description proceeds in connection with the accompanying drawings, in which:

Figure 1 is an elevational view of an engine starter with parts broken away to show the relay of the present invention installed therein;

Figure 2 is a top plan view of the starter shown in Figure 1;

Figure 3 is a vertical sectional view through the relay and terminal assembly, certain parts being shown in elevation;

Figure 4 is a view in rear elevation, with parts broken away, of the assembly shown in Figure 3; and

Figure 5 is a perspective view of a sub-assembly unit comprising the movable contact and terminal pin therefor.

The present relay and terminal assembly is designed to be accommodated in a cylindrical recess or well 2 in the electric starter 1, its function being to control the power circuit for the motor thereof. This assembly is constructed as a removable unit 3 as shown in Figure 3 and the well 2 is preferably, though not necessarily, formed in a bilobate motor casing or housing of the type disclosed and claimed in my copending application, Serial No. 450,038, filed July 7, 1942.

In the bottom of the well 2 is secured an insulating member 4 bearing a fixed cup-shaped contact element 5 secured by a terminal connection 6. A movable circular contact member 7 normally assumes a position of repose slightly above the fixed contact 5, the movable contact member being carried upon the lower end 8 of a plunger 9 attached to a movable core element 11 within

the solenoid 10. When the solenoid is energized the movable core element 11 is drawn toward a fixed core element 12 against the force of a compression spring 13. The said lower end 8 of the plunger is insulated from ground through the agency of insulating material 14 in a cupped portion 15 receiving the main body of the plunger embedded therein as shown. The cupped portion 15 carries a flange 16 serving as an abutment for a compression spring 17 urging the contact member 7 against a nut or head portion 18.

The travel of the plunger exceeds the clearance between the contacts so that when the movable contact member 7 engages the fixed contact 5 the plunger 9 continues its travel, compressing the spring 17 and carrying the nut 18 below the member 7 a short distance so as to increase the contact pressure and allow for wear on the contact faces. It will be appreciated that wear on the contact faces will not impair operation of the relay until there is no longer such excess travel of the plunger after closing of the contacts. To insure the best possible contact between the parts 7 and 5, the member 7 is mounted for free rocking movement as well as longitudinal movement upon the end portion 8. Return movement of the plunger under the influence of the spring 13 is arrested by contact of an insulating flange 14a with an insulating washer 19 bearing against an angle plate 20 supporting the solenoid on one leg thereof.

The angle plate 20 carries on its other leg a terminal portion 21 comprising the threaded member 22 for receiving a conduit coupling, and terminal pins such as 23, 23a and 24. The large terminal pin 24 is part of an integral terminal and contact sub-assembly 25 including also a conductor ring 26, a metal bellows 27, and the movable contact member 7, as shown in Figure 5. The various parts of this sub-assembly are preferably integrally united as by soldering or the like to provide a permanent good conducting path for large currents from the pin 24 to the contact member 7. The upper end of the bellows 27 is united with the conductor ring 26 which has a depending ear, or lug, 26a for carrying the terminal pin 24, and the lower end of the bellows is similarly united with the contact member 7, the length and stiffness of the bellows being such as to offer substantially no interference with the solenoid action and contact movement as previously described. The function of the bellows 27 is merely that of a concentric flexible electrical

connection of large current carrying capacity for the movable contact element 7.

When the assembly of Figure 3 is installed in the starter, or motor, or other electric power consuming device, the ring 26 seats on, or in, a tubular insulating liner 28 fitting within the well 2. The solenoid 10 then extends through an end opening 29 in the well 2, and the terminal portion 21 extends through a side opening 30 for connection with an electrical supply conduit. In the illustrated embodiment a pair of leads 31 and 32 from the solenoid coil are connected with the contact pin 23a and the stud 23b, the latter being connected to ground through a spring finger 33 secured in the bottom of the well 2. If the starter is provided with a governor the finger 33 may be insulatedly carried by the member 4 and wired to the governor operated switch, in the ground side of the solenoid circuit. The terminal pin 23 is provided with a soldering lug or the like 34 for connection with a circuit to a jaw meshing solenoid in the starter. The solenoid leads 31 and 32, and the power lead, constituted by the ear 26a, are seen to be disposed between the legs of the angle plate 20 so as to be housed within the well 2 along with the main contacts 5 and 7. The angle plate 20 with its associated solenoid and terminal portion preferably conforms to, and closes, the top and side openings 29 and 30 of the well 2.

While the present relay is particularly adapted to be housed in a well or recess in a motor frame having a bilobate extension on the commutator end, it may be mounted in any available space on or within any kind of power consuming device to be controlled, or it may be mounted apart from said device and provided with its own housing. Also, various changes may be made in the construction and arrangement, and certain features may be used without others. All such changes and modifications are deemed to be within the scope of the invention and the same is to be limited only by the scope of the appended claims and the prior art.

I claim:

1. A switch mechanism comprising a plunger, a contact member on said plunger, a stationary annular conductor ring surrounding said plunger, and a flexible metallic bellows surrounding said plunger and constituting an electrical connection between said movable contact member and said stationary conductor ring.

2. A switch mechanism comprising a plunger, said plunger having an insulated end portion, a contact disc slidably mounted on said end portion, a spring on said end portion for biasing said contact disc toward the extremity of said end portion, a stop on said extremity for retaining said contact disc against said biasing spring, a conductor ring around said plunger and insulated therefrom, and a flexible metallic bellows surrounding said end portion and said biasing spring and bonded at its respective ends to said contact disc and said conductor ring for energizing said contact disc.

3. A switch mechanism comprising a plunger, an insulating body on the end of said plunger, a flanged end portion for said plunger carried by said insulating body, a stop on the extremity of said end portion, a contact disc carried by said end portion, a spring bearing against said flange for biasing said contact disc against said stop, a conductor ring surrounding said plunger and insulated therefrom, a terminal post carried by said conductor ring, and a flexible metallic bellows bonded at its respective ends to said conductor ring and said contact disc for energizing said contact disc.

4. In a relay switch mechanism having a contact member on a plunger, a conductor ring surrounding said plunger and insulated therefrom, and a flexible tubular sleeve of conducting material surrounding said plunger and electrically united at its respective ends with said ring and said member, said tubular sleeve being exposed within and without to atmospheric pressure whereby said assembly has a large current carrying capacity and said ring serves as a stationary terminal for said movable contact member.

RALPH M. HEINTZ.
